(57) CLAIM

The ornamental design for a baseball novelty item, as shown and described.

DESCRIPTION

A portion of the disclosure of this patent document contains material to which a claim for copyright is made. The copyright owner has no objection to the facsimile reproduction by anyone of the patent document or the patent disclosure, as it appears in the Patent and Trademark Office patent file or records, but otherwise reserves all other copyrights whatsoever.

FIG. 1 is a plan view of a baseball novelty item, showing my new design, the bottom view being the mirror image thereof; FIG. 2 is a side elevational view thereof, the opposite side being a mirror image thereof;

FIG. 3 is a rear elevational view thereof;
